UNITED STATES PATENT OFFICE.

HECTOR DOWSON, OF COLUMBUS JUNCTION, IOWA.

SIGN.

1,260,882.

Specification of Letters Patent. Patented Mar. 26, 1918.

Application filed August 6, 1913. Serial No. 783,423.

To all whom it may concern:

Be it known that I, HECTOR DOWSON, a citizen of the United States, residing at Columbus Junction, in the county of Louisa 5 and State of Iowa, have invented certain new and useful Improvements in Signs; and I do hereby declare the following to be a full, clear, and exact description of the invention, such as will enable others skilled in 10 the art to which it appertains to make and use the same.

This invention relates to new and useful improvements in signs and has for its object the provision of a device which may be 15 easily and quickly attached to a frame which is secured to a wall or other supporting structure. In all cases the frame is to be set up and fastened in place before the sign is secured thereto.

20 Another object of my invention is the provision of such a device which may be easily constructed, cheap to manufacture, and effective in use.

With the above and other objects in view 25 I now proceed to describe my invention in the following specification and accompanying drawings, in which,

Figure 1 is a view in elevation of the blank from which my improved sign is 30 made,

Fig. 2 is a view showing the method of attaching the sign,

Fig. 3 is a view similar to Fig. 2,

Fig. 4 is a top plan view of the attaching means showing the same in position with relation to the sign.

Referring to the drawings by characters of reference 1 indicates the body portion or panel of the sign having formed integrally 40 therewith and at the edges thereof the outstanding tongues 2. This body portion is preferably rectangular in shape and is adapted to be formed of any suitable material from which signs may be made.

45 These tongues 2 are preferably bent as illustrated in Figs. 2 and 3 to form loops which extend rearwardly from the sign and are adapted to coöperate with the attaching members 3 having the tongues 4 formed 50 thereon. These tongues 4 are preferably bent in a manner similar to the tongues 2 and are adapted to coöperate therewith in holding the sign in position. The tongues 2 are spaced from each other, as clearly illustrated, to form the recesses 5 in which the fastening means are adapted to lie.

Suitable pins 6 are adapted to extend through the loops thus formed and hold the sign in position.

A frame 7, which may be formed of any 60 suitable material is provided and is adapted to act as a support for the fasteners which may be held thereto by means of screws, bolts, rivets or the like.

The plates forming the attaching members 65 may either extend rearwardly as clearly shown in Fig. 3 or may be bent downwardly at right angles, as illustrated in Fig. 2.

The loops formed on the edges of the sign 70 extend rearwardly so that when the device is in place the said loops will at no time project above or below the edges of the sign and present an unmarred appearance.

It will be clearly seen that with my improved sign the use of all fastening means 75 projecting through the surface of the sign is eliminated and it will be apparent that when it is so desired these signs may be interchanged without in any way defacing or marring them. Thus, it will be clearly 80 seen that in the use of my improved sign there are several advantages to be gained which will materially assist those interested in the art of sign making.

The panel loops are located on the rear 85 side of the panel wholly within the planes of the edges thereof; that is to say, the edges of the panel each define a plane and the loops are located wholly within these planes. The loops also extend inwardly and 90 rearwardly from the edges of the panel. This location of the loops renders them invisible from the front side of the completed sign. The attaching members are located 95 inwardly with respect to the panel loops, which renders them invisible from the front side of the sign, and which permits them to be swung into engagement with the rear side of the panel so that a number of the panels may be compactly assembled for shipment.

A sign panel constructed in accordance 100 with my invention is adapted to be delivered to the trade in condition to be readily and quickly secured to a stretcher. To attach the panel it is only necessary to swing the attaching members outwardly with respect to the rear side of the panel, apply it to the stretcher, and then swing the attaching members into engagement with the outer edges of the stretcher, as shown 105 in Fig. 3 of the drawing. If, however, the thickness of the stretcher is less the length 110

of the attaching members, the attaching members are, after being swung into engagement with the outer edges of the stretcher, bent downwardly into engagement with the rear side of the stretcher, as shown in Fig. 2 of the drawing. After the attaching members have been brought into proper engagement with the stretcher, nails or other suitable fasteners are passed through the members into the stretcher. The location of the attaching members with respect to the edges of the panel permits the panel to be secured to a stretcher smaller than itself, rendering the stretcher also invisible from the front side of the sign.

While in the foregoing I have shown and described the preferred embodiment of my invention I wish it to be understood that I may change the specific arrangement and combination of parts without in any way departing from the spirit and scope of my

invention as defined in the claim appended hereto.

What is claimed is:

A sign including a panel provided with a plurality of loops located on the rear side thereof, said loops forming integral extensions of the edges of the panel and extending inwardly and rearwardly from the edges and located wholly within the planes of said edges, bendable attaching members provided with loops, and pins passing through the loops on the panel and loops on the attaching members, portions of said attaching members being located inwardly with respect to the panel loops.

In testimony whereof I affix my signature in presence of two witnesses.

HECTOR DOWSON.
